UNITED STATES PATENT OFFICE.

WALTON W. BEALS, OF NEW YORK, N. Y.

FUEL BURNER.

Application filed December 13, 1926. Serial No. 154,354.

My invention relates to improvements in the class of fuel burners adapted to be fitted within the fire pots or combustion chambers of furnaces, heaters, boilers, stoves and the like, to admit air through the sides and the bottom into and throughout the ignited fuel mass within the burner. Such fuel burners, as known to me, have a standard or fixed size of openings in their sides whereby they are practically limited in operation to burning fuel of sizes limited to and appropriate for the sizes of said openings. With such a burner having side openings of such fixed sizes adapted for burning fuel of such fixed or standard sizes, too little or too much air is admitted through such openings for fuel of a larger or smaller size or of a different character than such burners can properly burn. Another disadvantage of such burners is that if fuel of a smaller size is used than that for which such burners are designed such fuel will more or less fall through the said side openings. Furthermore, ashes accumulate around the inside surface of said sides and clog the side openings thereof, thereby obstructing the entrance of the proper quantity of air, reducing the draft and air supply below the proper and necessary force and quantity which should be admitted to the burning fuel, for that size of fuel, with consequent impairment of the proper combustion of said fuel.

It is a well known fact that in order to secure the most nearly practically perfect combustion of solid fuels, the most nearly practical perfect and exact quantity of air necessary to rapidly and properly oxidize said fuels must be admitted to and throughout the burning fuel mass. In order to best accomplish such a result it is a prerequisite that the openings in the sides and at the bottom of fuel combustion devices be adjustable and adaptable to varying sizes and sorts of fuels. Especially is this necessary when bituminous, or soft, coal is burned and also the smaller buckwheat sizes of anthracite coal. The former having so much more volatile content than the latter, much more rapid oxidization must take place to properly burn it, while with the latter more draft must be employed against the surface of the fuel, or else air must be admitted more freely or rapidly than is necessary with the larger sizes of anthracite coal.

The object of my invention is to provide a burner or fuel combustion device, readily adaptable and adjustable for burning anthracite or bituminous coal, coke or other solid suitable fuels, regardless of the size or character of such fuels, whereby the most nearly practical proper or correct amount of air may be admitted in the most nearly practical proper or correct manner to the burning fuel within said burner to give the most nearly practical proper or correct and best combustion of fuel being burned therein, in accordance with its size or character, under all conditions of service, in heaters, furnaces, boilers, stoves and the like.

In carrying out my invention I provide a fuel burner adapted to fit within the fire pots or combustion chambers of furnaces, boilers, heaters or the like, having side walls comprising rotative bars spaced apart in such a way as to admit air therebetween into the fuel within the burner, and rotative on their longitudinal axes to shake and dislodge ashes that accumulate within the side walls of the burner, and a grate at the bottom of the burner adapted to be operated for shaking out ashes accumulated at and near the bottom of the fuel mass. The grate is preferably provided with means to vary the size of openings therein to support fuel of various sizes and to admit air to the fuel within the burner substantially in accordance with the requirements for the size of the fuel being used. I provide means for rotating the grate, and means for rotating the side wall bars of the burner with the rotation of the grate, whereby when the grate is rotated to clear the ashes from the bottom of the fuel mass within the burner the side bars will be rotated to clear the ashes from the sides of the fuel mass. The arrangement described is such, also, that the grate may be set in a definite position and the side bars set with relation one to another, independently one from the other, in accordance with the proper amount of air to be admitted at the sides and at the bottom of the fuel mass, such as required by and in accordance with the size or character of the fuel to be burned therein.

My invention also comprises novel details of improvement that will be more fully hereinafter set forth and then pointed out in the claims.

Reference is to be had to the accompany-

ing drawings forming a part hereof, where-
in

5 Fig. 1 is a partly sectional front elevation
of a portion of a water heater provided with
my improvement;

Fig. 2 is a horizontal section on line 2, 2,
in Fig. 1, parts being omitted;

Fig. 3 is a detail front elevation partly
broken away;

10 Fig. 4 is a vertical section substantially
on line 4, 4, in Fig. 3;

Fig. 5 is a plan view substantially on the
plane of line 5, 5, in Fig. 4, and partly
broken;

15 Fig. 6 is an inverted detail plan view;

Fig. 7 is a detail sectional view substan-
tially on line 7, 7, in Fig. 4;

Fig. 8 is an enlarged detail section sub-
stantially on line 8, 8, in Fig. 1;

20 Fig. 9 is a detail perspective of an end of
one of the upper guide members for the side
bars;

Fig. 10 is a detail side view of a portion
of the lower grate;

25 Fig. 11 is a section on line 11, 11, in Fig.
10;

Figs. 12 and 13 are perspective details
of fittings for adjustably supporting the
burner, and

30 Fig. 14 is a perspective view of the oper-
ative end of the grate operating the shaft.

Similar numerals of reference indicate
corresponding parts in the several views.

At 1 is indicated a hot water heater,
35 boiler or furnace having a combustion
chamber or fire pot at 2, an ash pit being
located at 3 provided with a door at 4, all of
which may be of any suitable or well known
construction. At 5 is a supporting mem-
ber of my improved burner, which may be in
30 annular or other desired form, having open-
ing 5^a for air, adapted to be suitably sup-
ported within the furnace or the like, as
within the ash pit thereof. The supporting
45 member 5 may be carried by cross bars 6
supported in seats 7 within the furnace or
ash pit. The parts 5 and 6 may be con-
nected together in any suitable way. I
have shown adjustable fittings for said parts
50 comprising spaced brackets 8 depending
from the support 5 and adjustably connected
thereto by means of bolts 9 operative in slots
10 in the support for lateral adjustment of
the brackets. The brackets 8 are shown
55 provided with interior spaces 8^a in which
blocks 11 are located, (Fig. 4), the blocks
having holes 11^a for the bars 6 and provided
with threaded studs 12 passing through
slots 8^b in the brackets, nuts 13 securing the
60 parts together. The blocks 11 are shown
rectangular at their main portions for ad-
justment in the spaces 8^a, the blocks ex-
tending at the ends opposite the studs 12
through slots 8^b in the brackets. I have
65 shown the blocks provided with heads 11^b

and reduced neck-like portions 11^c, (Figs. 4
and 13). The blocks are shown longer than
deep and their heads are correspondingly
arranged so that the blocks may be fitted
within the slots 8^c of the brackets, which
slots are longer than wide, and when the
blocks are within the spaces 8^a they may be
rotated one-quarter turn so that their heads
11^b will extend against the outer surfaces of
the brackets 11 to adjustably retain the
blocks in the spaces of the brackets. By the
arrangement described the brackets may be
adjusted for locating the support 5 in the
desired position respecting the bars 6. The
supporting member 5 may be supported 80
within the boiler or furnace in any other
desired way.

At 14 are side bars of my improved burner
which are spaced apart side by side, pro-
viding the outer wall of the burner, enclos-
ing a space for fuel, the bars being shown 85

annularly disposed. In the example illustrated
the side bars 14 are shown upwardly dis-
posed, for an annular burner, but it will
be understood that the bars may be hori-
zontally disposed, as for a rectangular fire
pot or combustion chamber. As illustrated,
the lower ends of the bars 14 are rotatably
90 supported upon the supporting member 5,
for which purpose I have shown said mem-
ber provided with spaced vertically dis-
posed bearing bores 15 within which the
lower ends 14^a of the bars are journaled,
95 said bars being shown provided with shoul-
ders at 14^b rotatably resting upon the sup-
port 5, whereby the bars are journaled in an
upright position. The upper ends of the
bars 14 are guided by guide-ring 16 adapt-
ed to fit within the fire pot or combustion
100 chamber 2, (Fig. 1), the guide-ring being
shown provided with radially disposed aper-
tures, shown in the form of slots 16^a, within
which the upper reduced ends 14^c of some
of the bars 14 are journaled, (Fig. 4). The
ring 16 may bear against the adjacent wall
105 of the fire pot or combustion chamber 2 to
maintain the ring and the upper ends of the
burner bars 14 in proper operative posi-
tion and to resist the flow of air between
the ring and the fire pot wall. The space
110 enclosed within the outer wall of the burner
may be filled as deep as desired with fuel, and
the fuel may be piled up with part of it rest-
ing upon the ring 16 and retained by the ad-
jacent portion of the fire pot or combustion
115 chamber wall. Gases generated from the
burning fuel will burn over the fuel on the
ring 16. The ring 16 may be made in any de-
sired way, either in a single piece or in several
120 pieces detachably connected together. I
have illustrated the ring 16 in several ar-
cuate sections or pieces connected together at
their ends. By preference the ends of the
ring sections 16 are reduced at 16^b, (Figs.
125 1 and 9), to overlap, and provided with slots
130

16^e through which the end portions 14^e of certain of the bars 14 project. I have illustrated means to detachably secure the adjacent ends of the sections of ring 16 together, comprising a bushing 17 having exterior threads 17^a and shoulder 17^b, upon which the adjacent ring section rests, the bushing being supported upon shoulder 14^a of the corresponding bar 14, the portion 14^e of which bar is journaled in the bushing, (Figs. 1 and 8). A nut 18 is screwed upon the threaded portion 17^a of bushing 17 and against the adjacent portion of ring 16, the nut and the bushing together securing the ring sections together. The end portions 14^e of the corresponding bars 14 are provided with means to retain the parts rotatively together, for which purpose I have shown washers 19 upon the nuts 18 and locking means, such as cotter pins 20, passing through the ends 14^e of the bars, whereby the appropriate bars are rotative within the bushings and the ring 16 is kept from rising from the bars. The bars 14 that are not journaled within bushings 17 are free to rotate within the slots 16^a of the ring 16. By the means described the diameter of ring 16 may be varied, within limits, to fit within fire pots or combustion chambers of different transverse diameters, and the radially disposed slots 16^a of the ring will permit appropriate positions of the upper ends of the bars 14 in accordance with the working diameter of the ring 16. The bars 14, on their sides, preferably taper upwardly to accommodate different diameters of the ring 16 so that there will not be too much space between the bars at the top and their bottoms will remain approximately equidistant when the ring is extended to its greatest or smallest diameter, and so that the bars will rotate freely with respect to one another when the ring is at its greatest or smallest diameter.

45 In order to provide more or less space between adjacent bars 14, for different sizes of fuel, said bars have a non-continuous perimeter or are non-circular, so as to more or less approach each other, according to set position. The bars 14 are preferably polygonal in cross section. I have shown the bars 14 as longer than wide, or elongated in cross section for producing more or less space between the bars to accommodate fuels of different sizes. To rotate the bars 14 I have shown the same provided, near their lower ends, with gears or pinions 21 in mesh with gear teeth 22, shown located along the exterior of a rotative member 23, which I preferably use as a portion of the burner grate. The member 23 is rotatively supported by the support member 5, for which purpose, and for the purpose of permitting ready rotation of member 23, I have shown the latter provided with an annular rim 24 bearing upon rollers 25, journaled upon studs or shafts 26 carried by upwardly extending lugs 27 on support 5, (Figs. 4 and 5.) There may be any desired number of the rollers 25 spaced apart for rotatively supporting 70 and balancing the member 23. To rotate the member 23 I have shown annularly disposed gear teeth 28 formed on the lower surface of said member, within the gear teeth 22, (Figs. 4 and 6), in mesh with a gear 29 carried by a shaft 30 which projects in position to be rotated for operating the member 23 and the bars 14. The inner end of shaft 30 is shown journaled in bearings 31 and 32, and the outer end of the shaft may 80 project through the front wall of the furnace or ash pit, if desired, (Fig. 1). The outer end of shaft 30 may be made polygonal, as indicated at 30^a, (Figs. 1 and 14), to detachably receive a crank handle. 85

The arrangement described is such that when shaft 30 is rotated or rocked in either direction the gear 29 and teeth 28 and will cause rotation of the member 23, and by reason of the engagement of gear teeth 22 with the gears or pinions 21 the side bars of the burner will be rotated and will shake and dislodge ashes that may have accumulated along said bars at the sides of the fuel mass in the space within the bars. By the arrangement described the bars 14 will be rotated substantially co-extensively, whereby substantially equal spacing between the bars will be provided, in any set position of the bars, to admit substantially corresponding 95 quantities of air between adjacent bars to the fuel mass within the burner. 95

Any suitable bottom grate may be provided for the burner. I have shown a frusto-conical grate 33 carried by the member 23 and provided with openings or slots at 33^a to permit the flow of air and of ashes through the grate. By the means described the rotation or rocking of shaft 30 will cause rotation or rocking of the grate as well 105 as the side bars 14, thus simultaneously shaking the ashes at the bottom and at the sides of the fuel mass. In order to accommodate fuel, such as coal, coke or the like, of varying sizes upon the grate I provide the latter with a cover 34 that is rotatively mounted upon the grate and provided with openings 34^a to register with the openings 33^a of the grate, the cover corresponding in contour to the grate, such as 110 being frusto-conical, (Figs. 4, 10 and 11). I have shown the grate provided with a flat top at 33^b and the cover having a correspondingly flat top to fit thereon at 34^b, (Fig. 4). To support fuel of different sizes and permit the flow of air through the grate in proportion as desired or best adapted for the size or character of fuel being used, I provide means to adjustably secure the grate and its cover together. For such purpose I have 115 120 125 130

shown an arm 35 secured to and depending from cover 34 and grate 33 is shown provided with a depending arm 36 adjacent to the arm 35 with means to adjustably connect said arms together, (Figs. 10 and 11). I have shown a screw 37 operative in a hole in arm 36 and adapted to fit in one or another of spaced openings 38 in arm 35 for securing the arms together. The arm 35 projects 10 through an opening or slot 33' in grate 33. With the parts in the position shown in Fig. 10 the openings 33^a and 34^a will be located in a mid-position respecting each other to accommodate fuel of an intermediate size, and 15 when the arms are secured together the grate and its cover will be rotated as a unit. If it be desired to use fuel of a different size the arm 36 may be adjusted to the left or right in Fig. 10 to accommodate fuel of a 20 larger or a smaller size and the arms will be secured together by the screw 37, whereupon the space through the registering openings 33 and 34 will be adjusted to a larger or smaller extent for supporting fuel of a desired 25 size and permitting the flow through the grate of the appropriate volume of air required by the size of the fuel.

Since the rotation of the bars 14 through the medium of the gear teeth 22 and the 30 pinions 21 will cause the edges of the bars to more or less approach each other, by reason of the polygonal or elongated transverse dimensions of the bars, it is desirable to keep the bars in proper relation to one another 35 according to the space desired between the bars with respect to fuel of different sizes. By stopping the rotation of shaft 30 in any desired position the gear teeth 22 will be correspondingly brought to rest and thereby 40 the bars 14 will be maintained in definite relation to one another, the ratio of the gearing being properly designed for such purpose. In order to indicate to the operator in what position it would be best to leave the 45 shaft 30 with respect to the size fuel he may be using, said shaft may be provided at its outer end with indicating means, such as letters or numerals. If five different sizes of fuel are intended to be used in the burner 50 the outer end of shaft 30 may be pentagonal, and at the end of the shaft adjacent to each flat portion of its surface may be located a numeral or letter to indicate the size of the coal to be used when the corresponding symbol is, say, upwardly disposed, as indicated 55 in Fig. 14. For instance, if No. 1 buckwheat anthracite coal is to be used the shaft 30 will be left with the numeral 1 upwardly disposed, and the gearing 21, 22 will cause 60 the bars 14 to remain in a definite relation, and so on, with the bars providing more or less space therebetween in either position in which the shaft 13 may be set.

With my improved burner installed in a 65 heater, boiler, furnace or the like the sup-

porting member 5 will be a sufficient distance from the side walls of the ash pit to permit the flow of air between them and into the space A between the bars 14 and the surrounding wall of the combustion chamber 70 to admit air between said bars to the fuel mass within the burner. The supply of air will not only be admitted from below in accordance with the relative positions of the openings of the grate and its cover to 75 supply a desired amount of oxygen to the bottom of the fuel mass, but also through the spaces between the bars 14 in quantity in accordance with the positions of the latter relative to one another, whereby combustion 80 of the fuel will be effected and perfected to a high degree by reason of the practicability to supply substantially the correct quantity of air to burning fuel according to the size and character at all levels and throughout 85 the burning fuel mass, whereby heat producing gases will be consumed to produce heat, within the combustion or fire chamber, and thereby increased radiation and intensity of heat is secured quickly through resulting 90 correct combustion of a relatively large quantity of the combustible constituents of the fuel with a relatively minimum production of residue, whereby economy in burning the fuel is effected. An advantage of my 95 improvement is that in order to increase or decrease the quantity of air admitted at any time to the burning fuel within the burner between the side bars 14, at the sides of the fuel mass, it is merely necessary to rotate 100 the shaft 30 to set the bars relatively to one another, whereby to adjust the spaces therebetween according to the quantity of air desired to admit to secure the most nearly practically correct combustion of the fuel in the 105 burner.

While I have illustrated and described a particular embodiment of my invention it will be understood that my invention is not limited to the details of construction and 110 relative arrangement of parts set forth, as the same may be varied, within the scope of the appended claims, without departing from the spirit of my invention.

Having now described my invention what 115 I claim is:—

1. A fuel burner comprising upwardly extending rotative bars at the outer sides of the burner providing an inner space between the bars for fuel, a diametrically expansible 120 ring having means rotatively guiding the upper portions of the bars whereby the latter may be maintained for rotation in different relatively spaced positions, a support for the lower portions of the bars, and means 125 to rotate said bars.

2. A fuel burner comprising a support, a grate movably carried thereby, a plurality of upwardly extending annularly disposed spaced bars pivotally supported by said sup- 130

port, and a ring comprising a plurality of sections pivotally guiding said bars at their upper portions.

3. A fuel burner as set forth in claim 2, in which the ring is diametrically expansible to fit within combustion chambers of varying diameters.

4. A fuel burner comprising a support, a grate rotatively carried thereby, a plurality of upwardly extending spaced bars pivotally supported by said support, means cooperative between said grate and bars for rotating said bars by and with the grate, and a ring pivotally guiding said bars at 15 their upper portions.

5. A fuel burner as set forth in claim 4, in which the bars are provided with means supporting said ring.

6. A fuel burner having an outer wall 20 comprising a series of upwardly extending bars enclosing a space for fuel, the bars being spaced and each bar having its side edges respectively cooperative with corresponding side edges of adjacent bars to admit air therebetween to fuel within the burner, a support upon which the bars are axially rotatively mounted, guiding means for rotatively maintaining the upper ends of the bars axially for the admission into 25 the burner between the bars of different quantities of air in different positions of the bars, said guiding means comprising a diametrically adjustable ring provided with openings rotatively receiving the upper portions of the bars whereby the diameter of the ring may be varied to fit within fire pots of different diameters and the upper ends of the bars may be correspondingly set relatively to one another, and means to rotate 30 said bars.

7. A fuel burner comprising a support, spaced upwardly extending bars rotatively mounted upon the support to admit air between the bars and enclosing a space for 45 fuel, a guide-ring for the upper portions of the bars provided with openings for rotatively guiding the bars comprising a plurality of sections, means to adjustably secure the sections together to vary the diameter of the ring, and means to rotate 50 said bars.

8. A fuel burner as set forth in claim 7, in which the means to secure the sections of the ring together comprise bushings having a 55 portion located in slots in the sections, and nuts cooperative with the bushings and with the sections to secure the sections together, the upper portions of some of the bars being journaled in the bushings.

60 9. A fuel burner as set forth in claim 7, in which the means to secure the sections of the ring together comprise bushings having a portion located in slots in the sections, and nuts cooperative with the bushings and 65 with the sections to secure the sections to-

gether, the upper portions of some of the bars being journaled in the bushings, the bars having shoulders near their upper portions upon which the bushings are supported.

70 10. A fuel burner having an outer wall comprising a plurality of spaced bars to admit air therebetween to fuel within the burner, means rotatively supporting said bars, a grate having openings and adapted 75 to support fuel and admit air into the burner, means rotatively supporting the grate, means to rotate said grate and means to rotate the bars by and with the grate.

80 11. A fuel burner having an outer wall comprising a plurality of spaced bars to admit air therebetween to fuel within the burner, means rotatively supporting said bars, a grate having openings and adapted to support fuel and admit air into the burner, 85 means rotatively supporting the grate, the grate being provided with a gear, the bars having gears in mesh with the first named gear, and means to rotate the grate, whereby the bars will be rotated with the grate.

90 12. A fuel burner having an outer wall comprising a plurality of spaced bars to admit air therebetween to fuel within the burner, means rotatively supporting said bars, a grate having openings and adapted to 95 support fuel and admit air into the burner, means rotatively supporting the grate, the grate being provided with a gear, the bars having gears in mesh with the first named gear, the grate being provided with downwardly disposed gear teeth, and a shaft having a gear in mesh with the downwardly disposed gear teeth for rotating the grate whereby the bars will be rotated with the 100 grate.

105 13. A fuel burner having an outer wall comprising a plurality of spaced bars to admit air therebetween to fuel within the burner, means rotatively supporting said bars, a grate having openings and adapted 110 to support fuel and admit air into the burner, means rotatively supporting the grate, the grate being provided with a gear, the bars having gears in mesh with the first named gear, and means to rotate the grate, 115 whereby the bars will be rotated with the grate, the grate being provided with an annular rim, and rollers upon which the rim is mounted for rotation.

120 14. A fuel burner comprising a support, a series of annular upwardly extending bars rotatably mounted upon the support providing a space for fuel, said bars being longer than wide in a transverse direction, means to rotate said bars for shaking the 125 sides of the fuel mass and whereby the bars may be set in different relations to admit varying appropriate quantities of air therebetween, and a ring having radially disposed slots rotatively receiving the upper 130

portions of the bars, the ring comprising a plurality of sections, means for adjustably connecting the ring sections whereby the diameter of the ring may be varied, the bars at the sides of their longer transverse dimensions tapering to accommodate different diameters of the ring without interfering one with another during rotation.

15. The combination of a combustion chamber with a fuel burner therein comprising a plurality of spaced upwardly extending rotative bars providing an outer wall having an inner space for fuel, a support rotatively carrying said bars at their lower ends, guiding means in ring-like form for the upper ends of said bars cooperative with the side wall of the combustion chamber to retain the bars, the guiding means being adapted to support fuel above the bars within said chamber, means to rotate said bars to dislodge ashes within the burner and a grate below the bars to sustain fuel

within the burner, said grate having openings to admit air into the burner.

16. The combination of a combustion chamber with a fuel burner therein having an outer wall comprising spaced upwardly extending rotative bars providing an inner space for fuel, means rotatively supporting the lower portions of the bars, a ring rotatively guiding the upper portions of the bars, said ring being of such diameter as to fit within said combustion chamber to retain the bars in operative positions and support fuel upon the ring within the combustion chamber, a grate at the lower portion of the burner to support fuel therein for combustion, and means to rotate said bars to dislodge fuel residue at the outer portion of the fuel mass within the burner.

17. A fuel burner as set forth in claim 16, provided with means to support the ring upon the bars.

WALTON W. BEALS.
